SCREEN FOR REFRIGERATOR CARS

Charles S. Johnston, Glencoe, Ill., assignor to
Transportation Specialties Co., Chicago, Ill., a
corporation of Illinois

Application May 29, 1944, Serial No. 537,777

5 Claims. (Cl. 62—15)

This invention relates to screen for refrigerator cars and more particularly to a screen adapted to be mounted in the ice bunker of a refrigerator car to provide for flow of air around the ice in the bunker.

One of the objects of the invention is to provide a screen which is strong and rigid in construction and is easy and inexpensive to fabricate and install in a car.

Another object of the invention is to provide a screen which provides maximum free circulation of air between the screen and a wall on which it is supported.

Still another object of the invention is to provide a screen which is protected against damage by a movable bulkhead or the like in the car.

A further object of the invention is to provide a screen which may serve as a support for a pivoted ice-grate or the like.

The above and other objects and advantages will be more readily apparent from the following description when read in connection with the accompanying drawings, in which:

Figure 1 is a partial transverse section thru a car equipped with the invention, with the car end in elevation;

Figure 2 is a front view of one of the supporting channels;

Figure 3 is a section thru the screen showing a supporting channel in side elevation;

Figure 4 is a partial section on the line 4—4 of Figure 2;

Figure 5 is a transverse section thru an alternative post construction; and

Figure 6 is an elevation of the construction shown in Figure 5.

In Figure 1 there is illustrated the end of a conventional refrigerator car having a bottom 1 and an outer side wall 2.

The side wall is connected to a Z beam 3 which supports a roof 4. Within and spaced from the side wall 2 is an inner wall 5 which may be formed of corrugated sheet metal. Sheathing 6 is supported between the side walls 2 and 5 and carries insulation 7 which extends below the sheathing substantially to the base of the car.

In refrigerator cars of the type shown, a bulkhead is employed spaced from the car end to form an ice bunker adjacent the car end. Ice is adapted to be supported in this bunker by a lower ice grate 8 formed of perforated metal sheets corrugated as indicated at 9 for strength. The sheets are turned down at their edges to provide vertical reinforcing flanges thru which the grates may be pivoted to lugs 10 carried by

supporting strips 11 on the end of the car. Thus the grates are pivoted to the car end and may be connected to the bulkhead when in use, being swung out of the way against the car end wall when they are not in use.

5 A floor grating 12 is supported below the lower ice grate on beams 13 and may serve as a lading rack when the car is used without refrigeration.

Adjacent the top of the car a screen indicated generally at 14 is provided and pivotally supported below the screen is an ice-grate 20 which can be swung to a retracted position adjacent the end of the car or which may be moved to a horizontal ice supporting position bridging the space between the car end and a bulkhead spaced therefrom.

The screen 14 is constructed according to the present invention of a plurality of sheet metal channel members 15 with their webs connected 20 to the car end and their flanges projecting outwardly from the car end at substantially right angles. The outer edges of the flanges are bent outwardly to form screen supporting strips 16 lying in a common plane. A screen 17 preferably formed of expanded sheet metal overlies the supporting strips 16 and is connected thereto by welding or by other desired fastening means. In this way, the screen is supported spaced from and substantially parallel to the car end wall so that air may circulate between the screen and the car end to be cooled by ice in the bunker compartment. In order to facilitate this circulation of air the flange portions of the channels 15 are formed with openings 18 so that air may circulate 25 freely both vertically and transversely around the channels. Thus, in the event any portion of the screen should be blocked, air circulation will not be seriously impaired.

In cars of this type it is customary to employ 40 movable bulkheads which may be moved to a retracted position adjacent the car end. In order to prevent damage to the screen by such bulkheads when they are in retracted position, blocking members may be carried by the screen to engage the bulkhead surface. As shown the blocking members indicated generally at 19 are formed by 45 relatively short sheet metal channels with their flanges extending thru the screen between the flanges of the channels 15. The flanges of the blocking members are secured to the post members 15 so that the web portions of the blocking members 19 project beyond the surface of the screen to engage the bulkhead and prevent it from striking the screen and to serve as a top 50 backing member for the bulkhead when it is in

a retracted position. If desired, the channels 19 may be cut out as indicated at 21 to provide for access to the fastenings by which the post members 15 are secured to the car end.

The channels 15 are preferably employed to support the pivoted ice-grate 20 and for this purpose they may carry hinge members 22. The hinge members as shown are formed by sheet metal straps bent around to provide openings to receive the hinge pintles 23. The straps 22 may be welded to brackets 24 which are in turn welded to the side flanges of the channels 15. Thus the channels 15 which are securely bolted to the car end wall serve both to support the screen and as pivotal support for the ice-grate 20.

Figures 5 and 6 illustrate an alternative construction of the post members which support the screen. In these figures the posts are formed by Z shaped strips having webs 26 lying substantially at right angles to the car end wall and perforated to provide for air circulation. Outer flanges 27 lie against and may be secured to the car wall and inner flanges 28 support a screen 29 spaced from the car wall. Blocking members 30 formed by short channels with their flanges at the top and bottom are secured to the posts as by welding to the webs 26 and project beyond the screen as shown. The webs of the blocking members may be formed with access openings 31.

While two embodiments of the invention are shown and described herein in detail it is understood that they are illustrative only and are not intended as a definition of the scope of the invention, reference being had for this purpose to the appended claims.

What is claimed is:

1. A screen for a refrigerator car comprising a plurality of parallel channel shaped strips adapted to have their webs secured to the car wall with their flanges extending outwardly therefrom, the flanges of said strips being perforated to provide for air circulation, the edges of the flanges being bent over at right angles,

and a flat foraminated screen overlying and secured to the bent over edges of the flanges.

2. A screen for a refrigerator car comprising a plurality of parallel sheet metal channels adapted to have their webs secured to the car wall with their flanges extending outwardly therefrom, the flanges being perforated to provide for air circulation, a screen overlying and secured to the edges of the flanges and held spaced from the car wall thereby, and relatively short channel members having their flanges extending between and secured to the flanges of the first named channels with their web portions projecting beyond the screen.

3. A screen for a refrigerator car comprising a plurality of parallel posts adapted to be secured to a car wall and including portions extending outwardly from the car wall, said portions being perforated to provide for air circulation, a flat foraminated screen secured to the outer surface of the posts and held spaced from the car wall thereby, and bumper members carried by the posts and projecting beyond the screen.

4. A screen for a refrigerator car comprising a plurality of parallel posts formed of relatively thin metal adapted to be secured at one edge to a car wall with relatively thin portions projecting outwardly from the wall, said portions being perforated to provide for air circulation, the outer edges of said portions being bent over to provide flat co-planar flanges, and a flat metal screen overlying and secured to the flanges and held spaced from the car wall thereby.

5. A screen for a refrigerator car comprising a plurality of parallel posts formed of relatively thin metal adapted to be secured at one edge to a car wall with relatively thin portions projecting outwardly from the wall, said portions being perforated to provide for air circulation, a flat metal screen secured to the outer edges of the posts and held spaced from the car wall thereby, and sheet metal bumpers welded to said portions of the posts and projecting beyond the screen.

CHARLES S. JOHNSTON.
